United States Patent Office

Des. 189,146
Patented Nov. 1, 1960

189,146

DISPLAY STAND FOR A WRISTWATCH OR SIMILAR ARTICLE

John Eula, 1432 E. Mauretania St., Wilmington, Calif.

Filed Feb. 23, 1960, Ser. No. 59,513

Term of patent 14 years

(Cl. D80—9)

Figure 1 is a perspective view of my display stand for a wristwatch showing my new design.

Figure 2 is a side elevation of the same.

Figure 3 is an end view taken from the line 3—3 of Figure 2.

Figure 4 is an end view taken from the line 4—4 of Figure 2.

I claim:

The ornamental design for a display stand for a wristwatch or similar article, substantially as shown.
